UNITED STATES PATENT OFFICE

BERTON L. BLANCHARD, OF LEOMINSTER, MASSACHUSETTS, ASSIGNOR TO F. A. WHITNEY CARRIAGE COMPANY, OF LEOMINSTER, MASSACHUSETTS, A CORPORATION OF MASSACHUSETTS

BABY CARRIAGE

Application filed April 15, 1929. Serial No. 355,058.

This invention relates to baby carriages and the object is to provide in such a carriage a body having a drop front which will be of superior appearance and possess advantages in use as will more fully appear as the description proceeds.

My invention may be well understood by reference to the following description of a single illustrative embodiment thereof shown by way of example in the accompanying drawings, wherein:

Fig. 1 is a fragmentary perspective view of a baby carriage showing the front end or foot of the body; and

Fig. 2 is a section on an enlarged scale on the line 2—2 of Fig. 1.

Referring to Fig. 1, I have there shown the body 3 as provided at the foot thereof with a panel 5 hinged at its lower end and adapted to be lowered to provide an extension of the reclining surface within the body. This panel closes up within a frame-like opening 7 and in this position forms a part of the rear end surface of the body as a whole.

It is important in baby carriages that they have an attractive appearance, and it is also desirable to avoid projections which might catch the clothing of the nurse or the bedding used in the carriage. To obtain these advantages, both aesthetic and practical, I provide for retaining the hinged panel in closed position by means of a latching mechanism received wholly between the front and rear surfaces of the end of the carriage and embodying a small, unobtrusive but convenient operating means exposed at the upper edge. Such latching means may conveniently take the form shown more specifically in Fig. 2.

Referring to Fig. 2, in the upper cross-frame member 9 of the panel 5 there may be provided a bevelled end latch bolt 11 sliding in the cylindrical casing 13 received in a bored hole in the frame member 9. The bolt is normally projected by the spring 15 interposed between the bottom of the casing and the bolt 11, the latter being retained in position by the shank 17 extending from the rear thereof through the bottom of the casing and provided with head 19. A key-way 21 in

bossed inwardly from the casing 13 and hold the bevel facing in the proper direction.

The bolt is adapted to snap into engagement with a keeper plate 25 secured on the opposed frame member 27. To provide for disengagement of the bolt the frame member 27 may be bored through from its upper edge in alignment with the bolt 11 in the closed position of the panel 5 to receive a casing 29 in which works a plunger 31 which may be depressed to repress the bolt out of engagement with the keeper. Herein the body of the casing 29 is annularly embossed inwardly to form a shoulder 33 supporting the plunger in its retracted position of Fig. 2 against the force of a retracting spring 35 which may be interposed between said shoulder and a handle, button or knob 37 connected to the plunger body 31 by a stem 39.

The handle 37 is exposed at the upper edge of the body and constitutes the sole exposed element of the latch mechanism, and when depressed it represses bolt 11, freeing it from the keeper and permitting the panel to be opened. It will be seen that the structure is very neat, the rear face of the carriage being in no way marred by extraneous attachments, and that projecting parts are eliminated.

I prefer to arrange the parts in such manner that opening of the panel 5 requires an additional movement after depressing the handle 37. It will be noted that with the structure shown in performing the latter action no substantial opening force is exerted on the closure, as is the case of a directly operated bolt mounted on the closure itself. Thus the likelihood of an infant in playing releasing the drop end to fall open and strike him is minimized.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

Claims:

1. In a baby carriage body a drop front

closing within a frame-like opening, a spring projected bolt received between the faces of said front, a keeper on the opposed edge of the frame, and a releasing device housed between the faces of the frame and having an operating handle exposed at the upper margin of the body and operable to repress the bolt.

2. In a baby carriage body a drop front closing within a frame-like opening, a spring projected bolt received between the faces of said front, a keeper on the opposed edge of the frame, and a spring retracted plunger housed in said frame in alignment with the bolt in the closed position of the front and having an end projecting at the upper portion of the body by which it may be depressed to unlatch the bolt and constituting the sole projecting portion of the latching device.

3. A baby carriage body having an opening in its end framed by sides, bottom and a top, a drop front hinged at its lower edge and closing into said opening, and a latching mechanism between the upper edge of said front and the top piece of the frame organized between the inner and outer bounding surfaces of said parts and comprising a plunger extending through the upper edge of said top piece to provide an operating handle thereat, said handle constituting the sole projecting portion of the latching mechanism.

4. A baby carriage body having an opening in its end framed by sides, bottom and a top, a drop front hinged at its lower edge and closing into said opening, and a latching mechanism between said front and the opposed frame member comprising a latch bolt and operating means therefor, said mechanism being received between the inner and outer bounding surfaces of said end and having a handle carried by and projecting from the edge of said frame member, said handle being depressible to release the latching mechanism and constituting the sole exposed portion thereof, said handle effective to exert solely an unlatching movement of the bolt to prepare the front for additional manipulation to open the same whereby the possibility of accidental opening of the front on inadvertent actuation of the handle is minimized.

In testimony whereof, I have signed my name to this specification.

BERTON L. BLANCHARD.
